ANTENNA SYSTEM

Laurance McConnell Leeds, Schenectady, N. Y.,
assignor to General Electric Company, a cor-
poration of New York

Application January 3, 1936, Serial No. 57,343

10 Claims. (Cl. 250—33)

My invention relates to a high frequency antenna system and more particularly to a means for feeding a half wave vertical antenna in such a manner as substantially to eliminate standing waves on the transmission line feeding the antenna.

It is well known to the prior art that a half wave vertical antenna has a desirable radiation field pattern for certain applications such as 10 police department use, because of its equal field intensity in all horizontal directions. Such an antenna usually requires feeding from one end. Because of its high end impedance, an impedance matching transmission line section has been inserted between the transmission line and the antenna. Although in the prior art the surge impedance of the transmission line has been matched by an impedance matching section, it has failed to eliminate standing waves on the 20 transmission line. This, of course, is due to the fact that the half wave antenna can not symmetrically load the impedance matching section. Since the antenna can only be connected to one arm of the section, a high impedance load to 25 ground is placed on one side of the section but not on the other. This unequal loading is reflected in the transmission line and standing waves result.

It is an object of my invention to provide a 30 means for connecting a transmission line to an impedance matching transmission line section in such a manner as substantially to eliminate standing waves on the transmission line.

It is a further object of my invention to connect a transmission line to an impedance matching section in such a manner as to balance any unequal loading placed on the impedance matching section by an antenna.

The novel features which I believe to be characteristic of my invention are set forth with particularity in the appended claims. My invention itself, however, both as to its organization and method of operation together with further objects and advantages thereof, may best be understood by reference to the following description taken in connection with the accompanying drawing in which Figures 1 and 2 represent two embodiments of my invention.

Referring to Fig. 1 of the drawing, I have indicated at 1 a half wave vertical antenna and at 2 a transmission line having an inner conductor 3 and an outer concentric conductor 4. Since the end impedance of the half wave vertical antenna is always relatively high and since the surge impedance of a concentric transmission line is much lower, a quarter wave impedance matching transmission line section 5 is inserted between antenna 1 and transmission line 2. Impedance matching section 5 comprises two parallel conductors 6 and 7 and a third conductor 8

which closes the bottom of section 5. An impedance matching section of this type is particularly well suited for connecting the transmission line to the antenna since it has a very low impedance at its closed end and a relatively high 5 impedance at its open end.

A high frequency source is indicated generally at 9.

In order that energy may be transferred from transmission line 2 to antenna 1 with minimum 10 loss, standing waves must be eliminated from the transmission line. To achieve this result two conditions must be satisfied; first, the transmission line at the point where it is connected to the impedance matching section must look into an 15 impedance which is equal to the surge impedance of the transmission line. In the second place, it must also operate into a balanced load. If either of the aforesaid conditions remains unsatisfied, reflection will occur and standing waves 20 will be established on transmission line 2.

Since it is impossible to connect a half wave, end fed antenna to a quarter wave impedance matching section without presenting an unbalanced load, it has been found that it is necessary 25 to counteract this unbalanced loading by connecting transmission line 2 to impedance matching section 5 in a non-symmetrical manner. If outer conductor 4 be connected to a point of minimum potential in impedance matching section 5, it is clear that there will be some point on arm 7 to which inner conductor 3 may be connected such that transmission line 3 will look into a balanced load. If the dimensions of the various 30 elements in the transmission line, the impedance 35 matching section, and the antenna, are properly chosen so that this point on arm 7 also corresponds to the point where conductor 3 must be connected to match the surge impedance of transmission line 2, standing waves will be substantially 40 eliminated from the transmission line.

By way of example one antenna system for transmitting a 30.1 megacycle wave which has been found to give highly satisfactory results has a transmission line whose surge impedance is 54 45 ohms and a quarter wave impedance matching section whose surge impedance is 490 ohms. The antenna pipe was 1½ inches in diameter and the quarter wave conductor arm 7 was of #8 wire spaced 13 inches from arm 6. When inner conductor 3 was connected to arm 7 at a point 15 inches above conductor 8, standing waves were substantially eliminated from transmission line 2.

Referring to Fig. 2 of the drawing, I have shown an open wire transmission line 10 having two conductors 11 and 12 feeding impedance matching section 5 rather than the concentric transmission line 3 of Fig. 1. The operation with an open wire transmission line is the same in every respect as that described in Fig. 1 with the 60

exception that the point at which conductor 12 is connected to arm 5 is generally found to be considerably higher up on arm 5 than in the concentric transmission line case, due to the 5 higher surge impedance of the two wire line.

While I have shown particular embodiments of my invention, it will of course be understood that I do not wish to be limited thereto since many modifications may be made both in the circuit arrangement and in the instrumentalities employed, and I therefore contemplate by the appended claims to cover all such modifications as fall within the true spirit and scope of my invention.

15 What I claim as new and desire to secure by Letters Patent of the United States is:

1. The combination comprising an impedance matching transmission line section having a high impedance at one end and a substantially zero impedance at the other end, said section including two substantially parallel conducting arms, a half wave antenna connected to one arm of said impedance matching section at its high impedance end, and a two conductor transmission line, one of said conductors being connected to said impedance matching section at its minimum impedance point and said second conductor being connected to an intermediate point on the unloaded arm of said impedance matching section.

2. The combination comprising an impedance matching transmission line section having a high impedance at one end, a substantially zero impedance at the other end, said section including two substantially parallel conducting arms, a half wave antenna connected to one arm of said impedance matching section at its high impedance end, and a concentric transmission line, the outer conductor of said transmission line being connected to said impedance matching section at a point of minimum potential, and the inner conductor of said transmission line being connected to an intermediate point on the unloaded arm of said impedance matching section.

45 3. The combination comprising a half wave antenna, a transmission line, an impedance matching transmission line section including two substantially parallel conducting arms connecting said antenna to said transmission line, said arms being electrically connected together at one end, said antenna being connected to one arm of said impedance matching section at its open end, and said transmission line being connected to said impedance matching section at 50 said electrically connected ends and to an intermediate point on the other of said arms, thereby to balance the unbalanced load placed on said impedance matching section by said antenna and thereby substantially to eliminate 55 standing waves on said transmission line.

60 4. The combination comprising a half wave antenna, a transmission line, and an impedance matching transmission line section including two substantially parallel conducting arms connecting said antenna to said transmission line, said transmission line being connected to said arms of said impedance matching section at different 65 distances respectively along said section, thereby to balance the loading of said impedance matching section to substantially eliminate standing 70 waves on said transmission line.

5. The combination comprising an impedance matching transmission line section including two substantially parallel conducting arms having one end electrically closed, a half wave end fed antenna connected to one arm of said impedance matching section at its open end, and means for transmitting high frequency signals to said impedance matching section, said means including means for balancing the unequal loading imposed on said impedance matching section by 10 said antenna.

15 6. In combination, an antenna, a transmission line, and an impedance matching transmission line section, said antenna and transmission line each being connected to said transmission line 15 section in an unbalanced relation thereto, and means to match the unbalance produced by said antenna by the unbalance produced by said transmission line, to cause said transmission line to operate into a balanced load.

20 7. In combination, a transmission line having one conductor thereof extending beyond the end of the other conductor to form an antenna, a second conductor shorter than said first conductor connected to said one conductor at the 25 point substantially adjacent the end of the other conductor and having a length substantially equal to a quarter of a wavelength of the wave on which said antenna operates, and means to connect said other conductor to said second conductor 30 at a point thereof selected to produce a minimum of standing waves on said transmission line.

35 8. In combination, a transmission line having one conductor thereof extending beyond the end 35 of the other conductor to form an antenna, a second conductor shorter than said first conductor connected to said one conductor at a point substantially adjacent the end of said other conductor and extending substantially parallel to 40 said first conductor for a distance of a quarter of a wavelength of the wave on which said antenna operates, and means to connect said end of said other conductor to said second conductor at a point thereof between the ends thereof.

45 9. In combination, a transmission line comprising two conductors having a length of a quarter of a wavelength of the wave on which said transmission line operates, said conductors being connected together at one end and open at 50 the other end, an antenna connected to said other end of one of said conductors, a high frequency apparatus, and means including said high frequency apparatus to connect said one end to the other conductor at a point thereof intermediate the ends thereof.

55 10. In combination, a transmission line comprising two conductors having a length of a quarter of a wavelength of the wave on which said transmission line operates, said conductors 60 being connected together at one end and open at the other end, an antenna connected to said other end of one of said conductors and high frequency apparatus connected between said two conductors at different points along the length 65 thereof selected in accordance with the resistance at the end of said antenna adjacent the end of said one conductor to which end said antenna is connected.
